UNITED STATES PATENT OFFICE.

CONRAD SCHAUMBURG, OF NEW YORK, N. Y.

SHOULDER-PAD ATTACHMENT FOR VIOLIN CHIN-RESTS.

940,405.

Specification of Letters Patent. Patented Nov. 16, 1909.

Application filed June 14, 1909. Serial No. 501,967.

To all whom it may concern:

Be it known that I, CONRAD SCHAUMBURG, a citizen of the United States, residing in the borough of Manhattan, city, county, and 5 State of New York, have invented certain new and useful Improvements in Shoulder-Pad Attachments for Violin Chin-Rests, of which the following is a specification.

The object of my invention is to afford a 10 simple, cheap and effective shoulder pad attachment for use in conjunction with the ordinary chin rest used on violins, an attachment which may be quickly and conveniently connected with, or disconnected 15 from the base plate or lower clamping member of the chin rest, and which will constitute essentially a substitute for the old fashioned, detached shoulder pad resting directly between and against the under side 20 of the violin and the shoulder of the player.

Bearing this distinctive feature in mind, the invention consists in the construction and arrangement of parts hereinafter described and claimed specifically, whereby 25 the "pad" may be instantaneously adjusted for use, or detached without disturbing the chin rest, leaving the latter and the violin without any extraneous projection or part, as will be more fully set forth in this specification.

In the accompanying drawings, Figure 1, is an elevation of the underside of a portion of a violin provided with my shoulder pad attachment; Fig. 2, is an elevation of the 35 same; Fig. 3, an elevation of the chin rest provided with my button plate; Fig. 4, an elevation of the upper side of my shoulder pad attachment, detached, and broken away in part; Fig. 5, is a section on plane of line 40 5-5 Fig. 4; Fig. 6, a view of the underside of the button plate; Fig. 7, an end view thereof, and Fig. 8, a view of a modification in which the buttons are attached directly to the lower clamping plate of the chin rest.

C, represents a chin rest of ordinary and well known construction held upon the violin V, by means of the clamping plate c, and the screw-couplings c', c'. In the accompanying drawings I have shown this 45 form of chin rest for convenience of illustration only, it being understood that my shoulder pad attachment may be used in conjunction with any chin rest having a lower clamping plate c, or the equivalent 50 thereof.

The buttons b, b, for my shoulder pad

attachment, may, if desired, be attached directly to the underside of this lower clamping plate c, as shown in Fig. 8, but I prefer to use a button plate B, from the 60 underside of which the buttons b, b, project, said button plate B, being formed with a lip or flange b', which is inserted between the clamping plate c and the edge of the violin. This flange b', is preferably formed 65 with a cushion b'', for contact with the violin. The use of the button plate B adapts my shoulder pad attachment for use in conjunction with any chin rest having a lower clamping plate without altering the latter, 70 although obviously it would be a simple matter to attach buttons directly to said clamping plate thereby dispensing in such case with the button plate B, which latter is however designed to accompany and form 75 a part of my shoulder pad attachment as sold in the market.

The plate P, constitutes the base of my shoulder pad attachment, and is formed with round holes p, p, coinciding in position 80 to and engaging with the buttons b, b, on the clamping plate c, or button plate B, as the case may be. It is also provided with a slidable locking plate Q, formed with holes q, q, having offsets q', q', of less diameter 85 by means of which the buttons are secured to the plate P.

Pivottally attached to the base plate P, is an extension arm E, of any desired form or configuration, excepting that it is relatively 90 short and flat as compared with what are known as shoulder pad rests designed to hold the violin away from the shoulder of the player. Attached to this extension or pad arm E is a pad e, of suitable shape and 95 construction, it being the equivalent of the old fashioned detached pad formerly used by players, and usually placed by them under the coat and between the shoulder and the violin for which latter it forms a cushion. 100 In fact, my pad e, is designed to perform the same function as the old fashioned detached pad, while overcoming the practical objections to the latter, among which were its liability to slip out of position, and even 105 to drop down and out of the coat when relieved of the pressure of the violin.

By pivotally attaching and making the pad arm E, adjustable on the base plate P, I am enabled not only to hold the pad firmly 110 in position, but also to adapt it accurately to the person, convenience and comfort of

the user. Furthermore, being entirely under the violin when in use, it is invisible; and may be instantly detached after playing by a simple movement of the slidable locking plate Q, and transferred to the pocket or otherwise disposed of without attracting attention.

What I claim as my invention and desire to secure by Letters Patent is,

- 10 1. The combination of a violin chin rest formed with a lower clamp member fitting on the under-side of a violin, buttons attached to said lower clamp member, a base plate formed with round holes engaging with the buttons secured to said clamping member, a locking plate slidable on said base plate, an extension arm pivotally attached to said base plate and adapted to be

turned thereon, and a shoulder pad attached to said extension arm, for the purpose described.

2. The combination of a violin chin rest formed with a lower clamp member fitting on the under-side of a violin, buttons attached to said lower clamp member, a base plate formed with round holes engaging with the buttons secured to said clamp member, a locking plate slidable on said base plate, an extension arm projecting from said base plate and a shoulder pad attached to said extension arm, for the purpose described.

CONRAD SCHIAUMBURG.
